UNITED STATES PATENT OFFICE.

EDWARD JOHN NEGUS AND FREDERIC CHARLES, OF LEICESTER, ENGLAND, ASSIGNEES,
BY MESNE ASSIGNMENTS, TO UNITED SHOE MACHINERY CORPORATION, OF PATER-
SON, NEW JERSEY, A CORPORATION OF NEW JERSEY.

MACHINE FOR OPERATING ON HEELS.

1,285,785.

Specification of Letters Patent. Patented Nov. 26, 1918.

Application filed May 7, 1917. Serial No. 166,989.

To all whom it may concern:

Be it known that we, EDWARD J. NEGUS and FREDERIC CHARLES, subjects of the King of England, residing at Leicester, Leicestershire, England, have invented certain Improvements in Machines for Operating on Heels, of which the following description, in connection with the accompanying drawings, is a specification, like reference characters on the drawings indicating like parts in the several figures.

This invention relates to machines for operating upon heels and is herein shown as embodied in the heel attaching machine of United States Patent No. 1,195,134, August 15, 1916, although its application is not limited to that or to any particular type of machine.

In certain classes of work, notably in attaching high heels to shoes or in attaching heels to high boots, it is of great convenience to the operator to have clearance between the opposed work engaging members of the machine. This facilitates rapid work by rendering it easy to place the boot upon the jack or the heel in the holder. An object of the present invention is to improve the construction of heelng machines in the respects discussed. The desired results are secured by automatic movement between the opposed engaging members in a direction transverse to their customary direction of approach for clamping the work, so that in work receiving position their work engaging faces are not only spaced as shown but are out of alinement with each other.

A feature of the present invention, accordingly, consists in the combination, with a heel engaging member or abutment, of yielding means, for example a spring, tending to move said member horizontally to an inoperative position out of alinement with the jack, and means for locking the member against the action of the spring at the limit of its horizontal path of movement. This locking function may advantageously be accomplished by an actuating mechanism of special construction operating first to move the abutment into alinement with the jack and then to lock it positively in that position.

These and other features of the invention

will be best understood and appreciated from the following description of a preferred embodiment thereof selected for purposes of illustration and shown in the accompanying drawings in which—

Figure 1 is a view in side elevation of portions of the machine of the patent above identified having the present invention embodied therein;

Fig. 2 is a view in front elevation of the head of the machine;

Fig. 3 is a detail of part of the operating mechanism for the movable heel engaging member.

The machine frame 28 as herein shown is provided with vertical bearings for a reciprocating plunger 6, opposite to which is mounted a stationary jack 26 in which the driver gang is located. The plunger 6 is operated by a lever 13 secured to a transverse shaft 34 journaled in the head of the machine frame. A lever 32 is secured to the shaft 34 outside the frame and is connected at its rear end to a treadle operated rod 31. A spring 23 serves normally to swing the lever 32 in such direction as to hold the plunger 6 in elevated position.

The upper heel engaging member 36 constituting an abutment, is mounted to slide transversely from front to rear in ways 30 formed upon the lower end of the plunger 6. A spring 19 connected to the base of the member 36 at one end and at the other to a bracket 20 normally holds the member 36 in its rearmost position. A stationary stop 21 is arranged to engage a shoulder 22 on the member 36 when the latter is moved forwardly, thus determining the operative position of this member.

Upon the outer end of the shaft 34 is secured an upwardly extending arm 2 forked at its upper end and having a transversely, freely rotatable pivot pin 3 extending through its forks. The pivot pin is bored to receive the end of a bar 4 which is adjustably secured to the pin 3 by a spring detent 7 mounted in the pin 3 and shaped at its inner end to engage teeth 6 cut in one side of the bar 4. At its forward end the bar is supported by an eccentric stud 8 set in a bracket 9 secured to the head of the machine. The forward end of the bar is

beveled as shown in Fig. 1 and its positions may be accurately adjusted by turning the eccentric stud 8.

The bracket 9 is provided with journals 5 for a short transverse shaft 11 carrying at its outer end a cam arm 12 which extends downwardly into the path of the end of the bar 4. At the inner end of the shaft 11 is secured a depending arm 14 terminating 10 in a long sleeve bearing 15. Free to slide in this sleeve 15 is a rod 16 the lower end of which has a hook engaging a horizontal pin 18 at the front of the base of the heel engaging member 36. The member 36 is 15 limited in its rearward movement by the engagement of the sleeve 15 with an abutment formed on the head of the machine frame.

The parts of the machine initially occupy the positions shown in full lines in Fig. 1 20 from which it will be seen that the operator has convenient opportunity for placing a long legged boot upon the jack 26. The treadle 33 is then depressed, elevating the rod 31 and swinging the lever 32 and the 25 arm 2. The bar 4 is thus moved forwardly and its beveled end forced against the cam arm 12 swinging the latter outwardly and forwardly and turning the shaft 11. The arm 14 is accordingly moved outwardly and 30 the member 36 drawn into its forward position as shown by dotted lines in Fig. 1. The bar 4 is so adjusted with respect to the arm 12 that the latter is operated during the initial movement of the bar and during 35 the continued movement of the bar the arm 12 rides upon its upper surface thus locking the arm 14 and the connected member 36 against return movement. It will be noted that the sleeve 15 and the rod 16 form 40 an extensible connection between the swinging arm 14 and the sliding member 36. The continued depression of the treadle lowers the plunger 6 through the lever 13 until its movement is resisted by the work clamped 45 between the two heel engaging members. Thereupon the treadle supporting arm 29 is depressed and the power operated mechanism of the machine started as fully explained in the patent above identified. The 50 final downward movement of the plunger 6 is caused by mechanism, not shown, operating on the lever 13.

After the operation of the machine the release of the treadle by the operator results 55 in the parts moving back to initial position in the reverse order. If it should be desired to render inoperative the automatic mechanism for moving the member 36 laterally, the hook of the rod 16 may be disengaged from the pin 18 and the rod 16 held up in the sleeve 15 by the insertion through a hole in the rod of a cotter pin 24.

Having thus described our invention, what we claim as new and desire to secure 60 by Letters Patent of the United States is:

1. A machine for operating on heels, having, in combination, a heel engaging member mounted to move vertically and horizontally, yielding means tending to move said member horizontally to an inoperative position, and means for locking the member against the action of the yielding means at one limit of its horizontal path. 70

2. A machine for operating on heels, having, in combination, coöperating heel engaging members one of which is arranged to slide transversely, a spring tending to hold said member out of line with the other member, an arm for moving said member in opposition to the spring, and means for positively locking the arm in position with the spring under tension. 75

3. A machine for operating on heels, having, in combination, a reciprocatory head carrying a sliding heel engaging member, a lever for moving the head, and a bar connected to said lever and constructed and arranged in its initial movement to shift said member with respect to said head and then to lock said member in operative position. 85

4. A machine for operating on heels, having, in combination, heel engaging members, and mechanism for controlling the position of one of the members comprising an arm arranged to be turned manually, a rotatable pivot pin in the arm, an operating bar adjustably connected to the pivot pin, a cam arm disposed in the path of the bar, and an extensible arm connected to the cam arm and the heel engaging member. 95

5. A heel attaching machine having, in combination, a horizontally stationary jack, an abutment member movable into and out of vertical alinement with the jack and vertically toward and from the jack, a treadle, and means, connecting the treadle and abutment member, so constructed and arranged that depression of the treadle will effect horizontal movement of the abutment member into alinement with the jack and vertical movement of said member into engagement with the work upon the jack. 105

6. A heel attaching machine having, in combination, a horizontally stationary jack, a gang of drivers working through the jack, an abutment member movable into and out of vertical alinement with the jack and vertically toward and from the jack, and means acting in a single movement to move the abutment member into alinement with the jack and vertically toward the jack into engagement with the work thereon. 115

7. A heel attaching machine having, in combination, a horizontally slideable heel engaging abutment, a rock shaft, connections for translating rocking movement of the shaft into sliding movement of the abutment, a longitudinally slideable bar, a cam arm secured to the shaft and having its end initially in the path of the bar, and means 125

130

for sliding the bar into engagement with and past the end of the cam arm, whereby the rock shaft is first turned to move the abutment and then locked.

- 5 8. A heel attaching machine having, in combination, a jack, a transversely slidable heel engaging abutment, a rock shaft, motion transmitting connections between the rock shaft and abutment, a sliding actuating bar for the rock shaft, an arm secured

to the rock shaft and projecting into the path of movement of the bar, and means for changing said path of movement, to vary the extent of movement of the rock shaft and abutment.

15

In testimony whereof we have signed our names to this specification.

EDWARD JOHN NEGUS.
FREDERIC CHARLES.
